UNITED STATES PATENT OFFICE.

CHARLES PIKE ANDERSON, OF SEATTLE, WASHINGTON.

GATE-VALVE.

1,092,421.

Specification of Letters Patent. Patented Apr. 7, 1914.

Application filed November 4, 1912. Serial No. 729,367.

To all whom it may concern:

Be it known that I, CHARLES PIKE ANDERSON, a citizen of the United States, residing at Seattle, in the county of King and 5 State of Washington, have invented certain new and useful Improvements in Gate-Valves, of which the following is a specification.

The object of this invention is the perfecting of gate valves to render them better adapted to ordinary service or where it is required to control a fluid under pressure, by the provision of a liner for the valve-body which serves both for the valve seats 10 and the valve packing, together with novel devices whereby such member is effectually held in operative position. These ends are attained by the means hereinafter set forth and illustrated in the accompanying drawings, in which—

Figure 1 is a vertical sectional view of a gate valve embodying my invention. Fig. 2 is a perspective view of the valve-body liner; and Fig. 3 is a similar view of the 25 frame member for securing the same in place.

The reference numeral 5 designates the body of the valve having aligned induction and eduction passages 6 which communicate 30 with a centrally disposed chamber provided with oppositely inclined wall surfaces 7. At the top of the valve-body is an extension 8 within which is a compartment 9 of a diameter greater than the distance between 35 the wall-surfaces 7 to afford shelves 10 at the upper ends of the respective wall-surfaces.

11 represents a cap detachably connected to the upper end of the extension 8 and is 40 formed with the usual extension 12 having a packing nut 13 at its top and through which passes the stem 14, having a suitable handle 15. The interior of extension 12 is screw-threaded to engage with threads provided on the stem for operating the valve. The stem has at its lower end a head 16 which is seated in a recess provided in the upper end of a wedge-shaped valve 17 having faces 18 which are inclined to be in the 45 same angular relations with respect to each other as the respective wall faces 8, or approximately so.

A liner of a yielding material, such as leather or lead, is provided for covering the 55 wall surfaces 7. Such liner is desirably

formed by a sheet of material which, as shown in Fig. 2, is folded medially of its length into a substantially V-shaped configuration to provide a loop 19 and two leaves 20 which terminate in outwardly directed flaps 21. Port openings 20' are provided in the respective leaves 20, as shown. This member is placed within the valve-body so that the leaves 20 will be juxtaposed with the wall surfaces 7 and the flaps 60 21 extend over the shelves 10, as clearly shown in Fig. 1. To secure such member to the body, I employ a frame member, shown detached in Fig. 3, comprising two spaced wedge-shaped side elements 23 connected by 65 a transverse bar 24 at their lower ends and by spaced plate elements 25 at the upper ends of the same. The remote edges 26 of plate elements 25 are formed of arcuate shapes so as to fit within the compartment 70 9 and afford a relatively large surface to bear 75 upon the flaps 20.

The parts being thus constructed, and the liner being first placed within the body, as above explained, the frame is introduced. 80 Screws 27 are then inserted through apertures 28 and 29 provided in said flaps and plate-elements and engaged in screw threaded holes provided in the shelves 10. By further screwing down the screws, the 85 frame member is correspondingly moved so that the bar 24 thereof engages in the loop 19 of the liner to effect a tension to the leaves 20 and which are ultimately clamped between the edges 23' of the frame elements 90 23 and the opposing surfaces 7 of the said valve-body chamber.

By making a liner of relatively soft material it is unnecessary to machine any valve faces which in gate-valves is an expensive 95 operation. Furthermore, the liners which, in this instance, serve as valve-seats are firmly wedged, so to speak, by the frame against the walls 7 and, being held about their edges, are consequently made well-adapted to withstand any duty to which they are likely to be subjected and endure 100 for a longer time than if otherwise secured.

By removing the cap 11 and withdrawing screws 27 the frame member may readily 105 be removed for replacing the liner.

What I claim, is—

1. A gate-valve having a liner provided with opposing ports which are arranged to respectively register with both the inlet and 110

outlet passages of the valve-body, a frame member adapted to be adjusted to stretch said liner and be subsequently fastened to the valve body for securing the liner thereto.

2. In a gate-valve, the combination with the valve-body having a chamber with inclined opposing walls and provided with shelves at the upper ends of the latter, of a substantially V-shaped liner having terminal flaps, a frame member comprising V-shaped side elements, a bar connecting the lower ends of the side elements, plate elements connecting the upper ends of the respective side elements, and screws extending through the adjacent plate elements and the flaps for securing the liner at the top to the valve-body, said side elements serving

to hold the liner about its lateral edges to the aforesaid walls.

3. In a gate-valve, the combination of a valve-body formed with a chamber having inclined opposing walls, a substantially V-shaped liner for said walls, a frame-member, and means for securing said frame-member to the valve-body for securing said liner to the latter, said frame-member also serving to clamp the liner about its lateral edges to the aforesaid walls.

Signed at Seattle, Wash., this 29th day 30 of October, 1912.

CHARLES PIKE ANDERSON.
